(57) **CLAIM**

The ornamental design for a ceiling fan blade iron, as shown and described.

DESCRIPTION

FIG. 1 is a perspective view from below of a ceiling fan blade iron in accordance with my design, illustrating the environment of said blade iron;

FIG. 2 is a perspective view from below of the ceiling fan blade iron in accordance with my design, illustrating the environment of said blade iron;

FIG. 3 is an enlarged perspective view of the ceiling fan blade iron in accordance with my design, illustrating the environment of said blade iron;

FIG. 4 is a bottom plan view of the ceiling fan blade iron in accordance with my design, illustrating the environment of said blade iron;

FIG. 5 is a top plan view of the ceiling fan blade iron in accordance with my design, illustrating the environment of said blade iron;

FIG. 6 is a rear end view of the ceiling fan blade iron in accordance with my design, illustrating the environment of said blade iron;

FIG. 7 is a front view of the ceiling fan blade iron in accordance with my design, illustrating the environment of said blade iron;

FIG. 8 is a perspective view of the ceiling fan blade iron in accordance with my design, illustrating the environment of said blade iron;

FIG. 9 is a bottom plan view of the ceiling fan blade iron in accordance with my design, illustrating the environment of said blade iron;

FIG. 10 is a perspective view of the ceiling fan blade iron in accordance with my design, illustrating the environment of said blade iron; and,

FIG. 11 is a top plan view of the ceiling fan blade iron in accordance with my design, illustrating the environment of said blade iron.

The broken lines showing environmental structure are for illustrative purposes and form no part of the claimed design. In FIG. 3 the fan blade is shown broken away to indicate indeterminate length.
